DFS. 2218

William H. Mackon of Toledo Ohio.

Letter Patent No. 2218. Dated Nov. 7th 1865

Design for a Monument to the Memory of Abraham Lincoln.

The Schedule referred to in these Letters Patent and making part of the same.

To all whom it may concern.

Be it known that I, William H. Mackon, of Toledo in the County of Lucas, and State of Ohio, Artist have invented a new and Original Design for a Monument to the Memory of Abraham Lincoln, late President of the United States of America, and I do hereby declare that the following is a true and accurate description referring back to the accompanying drawings and Photograph, and to the letters of reference thereon, of my said invention or Design.

The nature of my invention consists in providing a Memorial Design, from a new and original combination of different component parts; and in the new and original shape or configuration of the proposed monument or manufacture as shown by said Design.

What I claim as my invention and desire to secure by Letters Patent is the Design for a Monument to the Memory of Abraham Lincoln, late President of the United States of America as shown and described.

Witness,

Ira E. See.

Jas. G. French.

William H. Mackon.
